HAROLD V. COES, OF NEW HAVEN, CONNECTICUT, ASSIGNOR TO THE SENTINEL MANUFACTURING CO., OF NEW HAVEN, CONNECTICUT, A CORPORATION.

SELF-CONTAINED TIME-CONTROLLED OPERATING MECHANISM.

1,161,618.

Specification of Letters Patent. Patented Nov. 23, 1915.

Application filed February 20, 1915. Serial No. 9,561.

To all whom it may concern:

Be it known that I, HAROLD V. COES, a citizen of the United States, residing at New Haven, in the county of New Haven and 5 State of Connecticut, have invented a new and useful Improvement in Self-Contained Time-Controlled Operating Mechanism; and I do hereby declare the following, when taken in connection with the accompanying 10 drawings and the characters of reference marked thereon, to be a full, clear, and exact description of the same, and which said drawings constitute part of this application, and represent, in—

15 Figure 1 a view in front elevation of one form which my improved self-contained time-controlled operating-mechanism may assume. Fig. 2 a plan view thereof. Fig. 3 a view of the mechanism in rear elevation, 20 with its several levers in the positions due to them preparatory to being set. Fig. 4 a corresponding view showing the levers in the positions due to them after they have been set and during the operation of the timing- 25 mechanism proper. Fig. 5 a reverse plan view of the device. Fig. 6 a view in vertical section on the line *a*—*b* of Fig. 4. Fig. 7 a detached view of the timing-disk. Fig. 8 a detached plan view of the timing-lever.

30 My invention relates to an improved self-contained time-controlled operating-mechanism adapted to be used in a variety of situations where it is desired to perform an operation at the end of a predetermined period, such as in apparatus for automatic cooking by gas, oil or electricity, in water heaters, in japanning ovens, etc., the object being to produce a compact, convenient and reliable apparatus organized with particu- 35 lar reference to being easily adapted for use and readily removable in use.

With these ends in view, my invention consists in a self-contained time-controlled operating-mechanism having certain details 45 of construction and combinations of parts as will be hereinafter described and pointed out in the claims.

In carrying out my invention as herein shown, I employ a setting-lever 2 provided 50 at its lower end with a handle 3, furnished at its upper end with an index-pointer 4 and formed near its upper end with a square opening 5 receiving a square shoulder 6 upon the hub 6^a of a timing-disk 6^b, mounted upon 55 the front end of a main or winding arbor 7

to which the said lever is secured by a cap- 60 nut 8. The said index-pointer 4 sweeps over a graduated dial 9 formed upon a dial-plate 10 located directly in front of the main frame 11 of the apparatus, the said frame 60 being made of heavy sheet metal. The ar- 65 bbor 7 is journaled in the front and rear movement-plates 12 and 13 of a timing- mechanism which may be of any approved construction, the said plates being held together by ordinary movement pillars 14. A coiled spring 15 mounted upon the rear end of the arbor 7 is wound by the rotation thereof in counter-clockwise direction by the setting-lever 2, and when wound drives the 70 train of the timing-mechanism, the said train being sufficiently indicated for the present purpose (Figs. 3 and 4) by means of the main wheel 16, the pinion 17, the wheel 18, and the balance-wheel 19. At its for- 75 ward end, the arbor mounts the timing-disk 6^b rigidly secured to it, and formed with a timing-notch 21 receiving a tooth 22 formed upon the adjacent edge of a vertically ar- 80 ranged timing-lever 23 hung at its upper end upon a stud 24 in the frame 11, the said tooth 22 riding upon the periphery of the disk 6^b. The swinging movement of the lever 23 on the stud 24 is guided and limited by the passage of its lower end between 85 guide-plates 25, 26, secured by screws 27, 28, to the frame 11. A helical tripping spring 29 attached at its upper end to the arm 30 of the lever 23 and at its lower end to the screw 28, exercises a constant effort to hold the 90 edge of the tooth 22 against the periphery of the timing-disk 6^b, and also effects the entrance of the said tooth into the said notch when the notch is brought into registration with the said tooth by the clockwise rotation 95 of the disk 6^b, due to the unwinding of the spring 15. The said lever 23 is also formed with a lifting-arm 31 co-acting with a latch- 100 arm 32 forming an extension of an oper- ating-lever 33 mounted, as shown, upon a short shaft 34 the ends of which are journaled in two depending lugs or arms 35 formed integral with the main frame 11. The latch- arm 32 is formed with a nose 36 entering a notch 37 in the outer edge of the timing- lever 23 which is thus adapted to maintain the operating-lever 33 in its set position against the tension of the main or power- 105 spring 38 which is attached at one end to a lug 39 on the said arm 33, and at its other 110

end to a stud 40 in the frame 11. The shaft 34 also carries a coupling-arm 41 from which the coupling-rod 42 depends, the said rod 42 constituting, as it were, the coupling-member of my improved mechanism. In the particular mechanism shown, the rod 42 is formed at its lower end with a dovetail 43 for coaction with a corresponding dovetail 44 at the upper end of a connecting rod 45, the dovetails 43 and 44 being held together by means of a sleeve 46, but the particular form of the coupling-member 42 may, of course, be widely varied.

As shown, the winding-arbor is provided with a friction device 47 whereby it is frictionally connected with the main-wheel 16 as more fully shown and described in the co-pending application of Joseph W. Gibney, filed Feb. 4, 1915, Serial No. 6148. The said arbor 7 is thus frictionally coupled with a member of the escapement-train, whereby the setting-lever 2 may be operated to unwind the main or power spring 15 after the mechanism has been initially set. This permits the time-limit to which the device was initially set to be reduced to any desired extent or nullified altogether. I do not however limit myself to the use of friction coupling-means of the character described.

In the operation of my improved mechanism, the operating-handle 33 is first pulled down against the tension of the power spring 38 so as to cause the lifting-arm 32 to contact with the lifting-finger 31 of the timing-lever 23 in swinging the same so as to retract the tooth 22 from the notch 21 in the disk 6^b which is thus unlocked, as it were, and also the setting-lever 2 which may now be swung from left to right, or counter-clockwise, to sweep its index-pointer 4 over the graduated dial 9 to predetermine the period or length of time which must elapse between the setting of the device and its being tripped by the action of the time-train proper. The character and range of the graduation upon the dial 9 will, of course, be determined by, and conformed to, the character of the use. The movement of the lever 2 from left to right will also effect the winding of the main or power spring 15. The handle 33 must be held down to keep the tooth 22 from re-entering the notch 21, until after the setting-lever 2 has been moved enough to carry the said notch out of registration with the tooth which thereafter rides upon the periphery of the disk, whereby the said lever 23 is held in position for the engagement of the nose 36 of the latch-arm 32 with the shoulder at the bottom of the notch 37 in the said lever, all this being necessary to hold the coupling-rod 42 in its elevated position against the tension of the power spring 38 which is energized by the depression of the operating-lever 33.

the driving-spring 15 thereof will slowly turn the timing-disk 6^b in the clockwise direction until the expiration of the time-limit to which the device was set; when the notch 21 will be brought into registration with the tooth 22 at which time the tripping-spring 29 will act to swing the timing-lever 23 from right to left for the entrance of the tooth 22 into the notch 21 and the disengagement of the shoulder of the notch 37 from the nose 36 which will release the shaft 34 to the action of the power-spring 38 which will now be rocked and positively effect the depression of the coupling-rod 42 and the connecting-rod 45 with sufficient force to effect the operation of the device, (whatever its character may be) connected with the rod 45 the power of which may be augmented either by springs or weights, if desired, or by an electric motor set in operation by the descent of the said rod. On the other hand, when the operating-lever 33 is depressed, the manual power exerted upon it overcomes the tension of the power spring 38 and lifts the rods 42 and 45 and reversely operates the mechanism with which they are connected.

I call particular attention to the self-contained character of my improved apparatus which adapts it as a unitary organization, to be applied to and readily removed from the apparatus or device which it is desired to control on the basis of a predetermined time-limit. If any change is necessary in adapting my mechanism to the apparatus to be controlled, the change will be practically confined to the coupling-member 42. I particularly wish to point out that in my apparatus, the operating-lever supplying the power is organized as a part of the apparatus so as to co-act with the timing-lever which in turn co-acts with the timing-mechanism. I have shown no housing, but it will be understood that, if desired, the entire mechanism may be inclosed in a case of any suitable description.

I claim:

1. In a self-contained, time-controlled operating-mechanism, the combination with a timing-mechanism including a setting-lever and a timing-disk, of a timing-lever co-acting with the said disk, an operating-lever co-acting with the said timing-lever, and a coupling member connected with the said operating-lever, the said parts being combined in a unitary structure adapted as such to be applied and removed to the mechanism to be operated by it.

2. In a self-contained, time-controlled operating-mechanism, the combination with a timing-mechanism including a setting-lever and a timing-disk, of a timing-lever co-acting with the said disk, an operating-lever co-acting with the timing-lever which it

which it is held in its set position, and a coupling-member connected with the said operating-lever.

3. In a self-contained, time-controlled operating-mechanism, the combination with a spring-actuated timing-mechanism including a setting-lever and a timing-disk, of a timing-lever co-acting with the said disk, an operating-lever co-acting with the said timing-lever and when manually operated releasing the said disk, a spring for operating the said operating-lever when released by the timing-lever, and a coupling-member connected with the said operating-lever and adapted to be connected with the mechanism to be operated.

4. In a self-contained, time-controlled operating-mechanism, the combination with a timing-mechanism including a setting-lever and a timing-disk, of a timing-lever co-acting directly with the said disk, an operating-lever co-acting with the said timing-lever, and when manually operated moving the same to release the said disk, a coupling-member connected with the operating-member and serving to connect the device with the mechanism to be operated by it, and means for operating the said operating-lever when the same is released by the timing-lever and disk.

5. In a self-contained, time-controlled operating-mechanism, the combination with a frame, of a timing-mechanism including a

setting-lever and timing-disk, of a timing-lever co-acting with the said disk, an operating-lever mounted in the said frame, co-acting, when manually operated, with the said timing-lever to move the same into its set position, and a coupling-member connected with the operating-lever which is held in its set position by the timing-lever, all of the said parts being combined in a unitary structure adapted as such to be applied and removed to the mechanism to be operated by it.

6. In a self-contained, time-controlled operating-mechanism including a setting-lever and timing-disk, of a timing-lever, a spring therefor, an operating-lever, a power spring therefor, a latch-arm operated by the said operating-lever and co-acting with the said timing-lever for moving the same into its set position when the said operating-lever is manually operated, and a coupling-member connected with the said operating-member and serving to connect the unitary operating-mechanism with the device to be operated by it.

In testimony whereof, I have signed this specification in the presence of two subscribing witnesses.

HAROLD V. COES.
